LIQUID DELIVERY PUMP

Thomas L. Bonen, Chicago, Ill., assignor of one-third to D. C. Strauss and one-third to Charles W. Huck, both of Chicago, Ill.

Application June 15, 1938, Serial No. 213,759

14 Claims. (Cl. 103—96)

The present invention relates to gas compressors and more particularly to compressors adapted for use in refrigerator cooling units.

One object of the present invention is to provide a simple, compact, highly efficient compressor having a rugged, durable construction which will operate effectively for long periods of time without requiring attention.

Another object of the invention is to provide a compressor having but few moving parts which, when once assembled, require no adjustment.

A further object of the invention is to provide an oiling system for a compressor unit of the type described which will effectively deliver lubricating oil between all relatively moving surfaces whereby the compressor unit will be properly lubricated at all times during operation, and whereby oil will be retained in contact with substantially all exposed wearing surfaces during periods when the compressor is not operating.

A further object of the invention is to provide a combination of parts in a compressor of the type described which will enable the use of a reciprocating piston element in a hermetically sealed casing without involving the disadvantages which have heretofore existed in the reciprocating piston type unit.

A further object of the invention is to combine an improved oiling system with a reciprocating piston type unit in such a way that such unit may be employed in a sealed casing without necessitating inspection, repair or other attention for the life of the unit.

A further object of the invention is to provide an improved form of oiling system in devices which involve the use of a rotor element rotating on a normally vertical axis, in which parts of the oil propelling mechanism become operative in response to movement of the rotor element.

A further object of the invention is to provide a compressor oiling mechanism which will effectively operate with a relatively small quantity of oil.

To these and other ends the present invention resides in certain relationships and combinations of parts, all as will be explained in the following specification and particularly pointed out in the claims appended thereto.

In the drawings, illustrating a preferred embodiment of the invention:

Fig. 1 is a cross-sectional view, illustrating the compressor unit within its hermetically sealed casing;

Fig. 2 is a fragmentary cross-sectional view.

taken substantially at right angles to the view of Fig. 1;

Fig. 3 is a horizontal sectional view, taken on line 3—3 of Fig. 1, illustrating the cylinder, piston and valve blocks;

Fig. 4 is a horizontal sectional view, taken on line 4—4 of Fig. 2, illustrating the upper surfaces of the valve block and the eccentric portion of the stationary bearing element;

Fig. 5 is a horizontal sectional view, taken on line 5—5 of Fig. 1, illustrating the oil propelling mechanism; and

Fig. 6 is a horizontal sectional view, taken on line 6—6 of Fig. 1, illustrating the lower end of the oil conduit and the duct which forms the connecting passage between the oil conduit and the oil propelling mechanism.

Similar reference numerals throughout the several views indicate the same parts.

The compressor unit, as herein disclosed, comprises a hermetically sealed housing supporting the field winding and laminations of an electric motor. The armature or rotating part of the motor is arranged on a rotor element in the form of a sleeve which rotates with the armature around a spindle or stationary bearing element. Also mounted to rotate with the rotor is a cylinder block having cylinders formed therein containing pistons which are caused to reciprocate within the cylinders as the cylinder block rotates, this being due to the fact that the pistons are connected through a combined valve and crank block element to an eccentric spindle or crank element at the upper end of a main, concentric, stationary bearing element.

The lower portion of the casing preferably constitutes an oil reservoir which delivers oil into an oil propelling mechanism formed in part on the stationary bearing element and in part on the rotor element, the stationary bearing element being formed with conduits through certain of which oil may be delivered to all moving surfaces and through certain other of which gas is delivered to the compression chambers of the cylinders. An arrangement of passages is also provided for redelivering the oil to the oil reservoir.

Referring more particularly to the drawings, the hermetically sealed casing, indicated at 10, may be constructed in any desired way for convenient assembly with a supporting base. The bottom wall of casing 10 is provided with an opening to accommodate the intake conduit, indicated generally at 11, and at some other suitable point, preferably near the top of the casing 10, there is provided a discharge fitting 12 for a

pressure line to conduct gas under pressure to the usual receiver from whence it may pass successively to the usual condenser and evaporator and thence back to the intake or suction line 11.

8 Suitable cooling fins 13, 13 are formed on the casing 10. These fins may be of conventional form.

Within the casing 10 are preferably mounted all of the operating parts of the compressor unit. Secured to the lower wall of casing 10 is a spindle or stationary bearing element, indicated generally at 14. On this spindle there is rotatably mounted a rotor element, designated generally at 15. At the upper end of the rotor, and rotatable therewith, is the compressor unit proper, designated at 16.

The spindle or stationary bearing element 14 comprises a base flange 17, having an upstanding annular casing 18 fitted thereon, a main, concentric bearing 19, and a supplemental, eccentric bearing or crank element 20. The base 17, as illustrated, is preferably formed with bolt openings 21, 21 arranged to register with openings 22, 22 formed in the bottom wall of casing 10 whereby the stationary bearing element can be rigidly secured to the casing. A gasket 23 is preferably employed between the base 17 and casing to insure a gas-tight connection.

The rotor element 15 is preferably formed as a part of an electric motor 24 which comprises a rotatable armature 25, and a stator comprising field laminations 26, and field windings 27. The armature 25 may be conveniently wedged or keyed to the rotor 15 and a flange 28 is preferably formed near the upper end of rotor 15 against the underside of which the armature is held.

Suitable supporting means, herein shown as an angle ring element 29, is secured to the casing 10 to support and firmly hold the stator element of the motor 24.

Current is led to the winding 27 through conductor element 30 passing to the outside of casing 10 through a sealed joint 31.

45 The rotor element 15 is supported on and is fitted to the stationary bearing element 19 at several points. The lower portion of the rotor element 15 is formed with an annular cut providing a horizontal bearing surface 33 which rests upon 50 the top edge 34 of the annular casing 18, and providing a downwardly projecting ring element 35 having a surface 36, formed to provide a slight clearance relative to the inner edge surface of casing 18. The bearing element 19 is provided 55 with a lower bearing surface 38 and an upper bearing surface 39. Between these bearing surfaces the element 19 is preferably reduced in diameter to avoid excessive friction between the rotor and element 19 and to facilitate the return 60 flow of oil as will be later pointed out.

The compressor mechanism 16 comprises essentially a cylinder block 41 connected to the rotor 15, and a piston block 42 connected to the eccentric bearing element, or crank 20 by means of a crank and valve block 43. The cylinder block 41 has formed therein cylinder openings 41a and 41b. This cylinder block is supported on the flange 28 of the rotor and preferably is secured thereto by a pair of machine bolts 44, 44, fitted within openings 45, 45, formed in the cylinder block and having their lower ends threaded into tapped out openings in the flange 28. In order to facilitate the fitting of the cylinder block on to the flange 28, the cylinder block is formed with

a pair of depending portions 46, 46, bearing laterally against opposite sides of the flange 28.

The rotor 15 is provided with an upstanding ring portion 47 forming a continuation of the bearing surface and extending above the surface of the flange 28 to a point approximately in line with the upper end of the concentric bearing element or spindle 19. The cylinder block is formed to loosely surround the portion 47, leaving a space 48, facilitating oil return as will be presently described.

The cylinder heads 51, 51 are each formed with a discharge valve assembly indicated generally at 52 to be presently described.

The piston block 42 preferably comprises a 15 cylindrical member having an integrally formed piston at each end thereof designated at 53 and 54 respectively. The pistons are formed with open ended ducts 55 and 56, respectively, extending from front to rear of the pistons. In order 20 to maintain the piston block 42 against rotary movement with respect to the cylinder block there is preferably formed at the top of the piston block a groove 58 having fitted therein a guide shoe 59, secured in fixed relation to the cylinder block by a machine screw 60 preferably having an unthreaded portion 61 thereof fitted into an opening in the guide shoe 59.

The cylinder block is preferably formed with a cut-away part indicated at 62, forming an oil 30 chamber extending from the lower side of the cylinder block to a point above the piston block; see Figs. 1, 2, and 3.

For the purpose of facilitating distribution of oil the crank and valve block 43 is provided at the top thereof with grooves 63, 63 and 64, 64, see Fig. 4. This block 43 closely fits laterally between the rear faces of the pistons and the central portion of the piston block rests on the crank block, see Figs. 1 and 2. The top of the 40 spindle is so formed with relation to the crank block and piston block that a slight clearance space will be provided at 65 for the distribution of oil entering at this point.

Delivery of oil to the compressor parts is made 45 through a delivery conduit 66, formed in spindle 19, by means presently to be described.

The details of the gas compressor mechanism will now be particularly described. As previously indicated, the gas enters the casing 10 through 50 the suction or intake line 11. A connecting part 68, preferably formed as an extension of the spindle 19, projects through the bottom of casing 10. This part 68 is interiorly threaded to receive a threaded plug fitting 69. The suction tube 70 is suitably joined to plug 69, and a gasket 71 is provided to insure a tight connection between parts 68 and 69. A check valve guide 72 is fitted against the under side of flange 17 at the lower end of a gas conduit 73, extending vertically of the spindle 19 and forming a continuation of the suction tube 70. This valve guide 72 embraces one end of a coil spring 74 bearing at its other end upon a movable check valve disc 75 normally closing the opening in the plug 69 but permitting inflow of gas into conduit 73 when the operation of the compressor mechanism causes sufficient suction at this point.

The conduit 73 extends upwardly through the concentric bearing element or spindle 19 and into the eccentric portion 20 and terminates in a widened port 76 which, in the present instance, extends over approximately a ninety-degree angle of the horizontal cross-section of the eccentric portion 20. Ports 77 and 78 are formed, one on

each side of the combined crank and valve block 43 and serve to periodically connect the port 76 with the piston ducts 55 and 56.

As indicated in Fig. 3, the motion of the rotor 5 is preferably clockwise. Thus, as the piston 54 is carried around by the cylinder block it will move relatively to the block from an outer to an inner position. In Fig. 3, it is represented in substantially its innermost position. While the 10 piston 54 has been moving thus, the opening 56 through the piston, the port 78 and the port 76 have all been in free communication for somewhat more than ninety degrees of travel. During this time the space between the end of the 15 cylinder and the cylinder head has been increasing from a mid-position to a maximum position. The discharge valve 52 in the piston head remains closed during this period as it is designed to open under internal pressure and to stay closed during 20 internal suction. As soon as the rotor has turned clockwise a short distance beyond that illustrated in Fig. 3, the port 78 will have passed out of communication with the widened port 76 so that the gas that has just been drawn into cylinder 41a will become temporarily trapped therein. As the cylinder block continues to rotate, carrying the pistons therewith, the piston 54 will gradually approach the end of the cylinder and build up a pressure which will cause the 25 discharge valve 52 to open, and gas under pressure will be expelled into the interior of the casing 10. This cycle then continues alternately with each cylinder and piston constantly building up pressure within casing 10. As pressure is built up the compressed gas is discharged through the discharge fitting 12.

The discharge valve assembly 52 will now be described. As the discharge valve constructions are identical a description of one assembly will suffice. The above mentioned cylinder head 51 is arranged to close the end of the cylinder and is provided with a port opening 79 centrally thereof to permit flow of gas from the cylinder. The cylinder head 51 is in the form of a disc and 45 is embraced by an outer casing element 88 having suitable openings or perforations therein to permit the discharge of gas into the interior of casing 10. A pin 81 is secured to the casing 88 upon which is slidably mounted a movable valve member 82. A coil spring 83 is engaged with the member 82, being retained therein by a channel 84 cut into the rear face of the member 82. A thin disc 85 is provided to close the opening 79 and a coil spring 86, retained in channel 87, 50 formed in the front face of member 82 bears against the disc 85 to normally retain it in place over the port 79. The disc 85 is preferably arranged to be opened with a tilting motion and, for this purpose, a small pin 88 is secured in the member 82 in position to contact the edge of disc 85 when the latter moves away from the opening 79. As the edge opposite pin 88 is free to move the greater distance, the disc 85 will be thus caused to tilt somewhat upon opening.

65 The valve member 82 is held away from the cylinder head plate 51 by means of a castellated ring 89 formed on its face. This ring bears normally against the rear face of plate 51, being disposed in a circular recess in the rear face of such plate.

70 The oiling system will now be more fully described. The oiling system is such that only a relatively small amount of surplus oil will be required to insure complete lubrication of all relatively movable surfaces at all times. According

to the present disclosure, oil is fed from a supply chamber to a channel within which is operatively arranged a part adapted to move in response to movement of the rotor element 15 whereby the oil in the channel is set in motion to cause it to rise through the oil conduit 66 by means of which the oil is distributed to the various parts of the device. In the present instance, the supply of oil is placed in the casing 10, it being only necessary to fill the casing to a shallow 10 depth. A channel 90 is provided in the lower part of spindle 19. This channel is preferably in the form of a circular groove extending entirely around the base portion of spindle 19, see Figs. 1, 2 and 5, and is enclosed by the previously 15 mentioned annular casing 18. The top part of channel 90 is closed by the ring portion 35 on the rotor 15. In the present instance the ring portion 35 is provided with a plurality of propelling elements 91, formed as extensions of the 20 ring portion 35 and separated from each other by segmental cuts 92 leaving spaces or pockets between the propelling members 91. Four members 91, and four pockets 92 are herein illustrated but it is to be understood that a fewer or greater 25 number can be employed.

An opening 93 (see Fig. 5) is formed through the upstanding annular casing 18 to allow oil to be conducted from casing 10 into channel 90. It is apparent that any oil that is present in 30 channel 90 during movement of the propelling elements 91 will be set in motion in the direction of movement of the elements 91. Advantage is taken of this movement of the body of oil in the channel 90 whereby the oil is caused 35 to flow up through the conduit 66. For this purpose the channel 90 is formed at its outer periphery with a portion of restricted width this being provided by leaving an inwardly projecting circumferential portion 94 extending inwardly a distance so as to make a snug fitting contact with the outer faces of the propelling elements 91, 91 as they rotate with the rotor 15. The inwardly extending face of the portion 94 provides a baffle element having an axially extending face for deflection of the oil out of the channel in a manner presently to be described. An additional, or booster, opening 95 is preferably formed through the annular casing 18 somewhat beyond the portion 94 for the purpose 45 of accentuating the action of the oil propelling mechanism. This opening may be dispensed with, if desired, but, when employed, acts to materially increase the efficiency of the unit. When the direction of movement of the propelling elements 91, 91 is clockwise, as indicated by the arrows in Figs. 3 and 5, there will be provided, just in front of the baffle portion 94 (as related to the direction of movement) a 50 duct 96, formed as a vertically or axially extending cut in the casing 18.

The duct 96, as indicated in Figs. 5 and 6, is preferably crescent shaped in horizontal cross-section, and may be formed by machining out a portion of the inner wall of the casing 18.

As best indicated in Fig. 1, the duct 96 preferably has its upper end substantially aligned with the upper limit of channel 90 and the duct extends downward to connect with a laterally or radially extending conduit 97 connected, in turn, to the conduit 66. Thus, when the propelling elements 91, 91, due to their rotary movement within the channel 90 cause the body of oil in channel 90 to be set in motion, it is apparent that the oil will move freely in the 7

channel 90 with the elements 91, 91 until the narrow part of channel formed by the baffle portion 94 is reached. No more oil can pass through this section of channel 90 than will be contained in one of the pockets 92. As a result of this relationship of parts a portion of the moving stream of oil will strike the face of the baffle 94 and tend to pass into the duct 96 and thence through conduit 97 and up through the conduit 66 to deliver lubricating oil to the cylinder and piston assembly. As oil is diverted from the channel 90 into the conduits 97 and 66, it is apparent that additional amounts of oil will enter through openings 93 and 95, this being caused by the suction developed due to forcing oil out through conduit 66.

It is also to be noted that the tendency of the oil stream to be diverted into duct 96 and conduits 97 and 66 will be proportionate to the counter pressure existing at the discharge end of the conduit 66. It is also apparent that changes in the relative sizes of the various parts, such as the channel 90, the propelling elements 91, 91, the duct 96, and the openings 93 and 95 will produce different degrees of oil pressure within the conduit 66.

It may be pointed out that, while the result of diverting the oil into duct 96 is produced in part by restricting the width of chamber 90, this result is accentuated by the centrifugal force developed when the body of oil is set in rapid motion around the channel 90. The body of oil is caused by centrifugal force to press against the outer wall of channel 90 and, as soon as any increment of oil arrives at the duct 96, a portion of such increment is forced down into the duct 96. At this point the centrifugal force, previously acting upon the body of oil will be converted into centripetal force, causing the oil to flow through the radially extending duct 97 and up through conduit 66. Succeeding portions of the moving oil body continue to deliver increments of oil to the duct 96 with the result that there will be a substantially uniform and continuous flow of oil, under considerable pressure, set up through duct 96 as soon as the rotor 15 begins to rotate at appreciable speed.

The action of the oil propelling unit is not positive but is at all times influenced by the amount of counter pressure existing in the conduit 66. Even if the conduit 66 were to be completely blocked no harm would result to the oil propelling mechanism.

The opening 93 is preferably somewhat restricted at its inner end, as indicated in Fig. 5. The opening 95 is spaced an appreciable distance from the opening 93, it having been found, in practice, that when this opening 95 is spaced approximately 45 degrees beyond the opening 93 very satisfactory results will be obtained.

As best illustrated in Fig. 5, the front faces of the propelling elements 91, 91 are inclined forwardly relative to a radial line extending from the center of the stationary bearing element 14. This inclination or pitch in the faces of the propelling elements 91 has the tendency of retaining oil at this point and provides for somewhat more efficient delivery of oil into the duct 96 when the faces of the individual propelling elements reach a point opposite the duct 96.

As stated above, the supply of oil is delivered directly into the casing 10, and while the amount of oil may vary, it has been found satisfactory to fill the casing 10 to substantially the level indicated by the broken lines in Figs. 1 and 2.

The level of oil in the casing 10 is preferably such that, when the device is in operation, the oil will not be drawn into the openings 93 and 95 so rapidly as to cause the level to lower at this point sufficiently to permit the inflow of gas through these openings and through the oil propelling mechanism.

When the oil passes up through conduit 66, the major portion of the stream will be delivered at the top of the eccentric portion 20 of the spindle or stationary bearing element 14 where a small space is preferably left between the top of the eccentric portion and the adjacent under surface of the piston block, as previously described. Part of the oil will be forced between the contacting surfaces of the block 43 and eccentric portion 20. The major portion of the oil stream will pass through the grooves 63 and 64, certain of which will always be in direct communication with the chamber 62 in the cylinder block during operation of the unit. In this manner, the inner end surfaces of the pistons will at all times be operating in a bath of oil.

In order to effectively deliver oil to the lower end of the combined crank and valve block 43, there is preferably provided a duct 98 leading from the conduit 66 and connected with a groove 99 preferably formed just above the point of juncture between the eccentric portion 20 and the concentric portion 19 of the spindle or stationary bearing element 14. Thus, a portion of the oil in passing up through conduit 66 will pass out through the small duct 98 into the groove 99, from which it will be forced both upwardly and laterally to effectively lubricate the contacting surfaces between the block 43 and the bearing element.

In order to provide for the return of oil there is preferably formed in the concentric bearing portion 19 a spiral groove 100 which, as indicated in Fig. 1, preferably extends from the upper end of the concentric bearing portion 19, down to a point near the lower end of the portion 19 where it is joined to an annular groove 101 formed in the portion 19. The oil passing into the groove 101 is preferably carried away from this groove through a duct 102 formed in the rotor element 15. By this arrangement it is apparent that oil passing down through the spiral groove 100 and into the annular groove 101 will constantly pass out through the duct 102, thence back to the main body of oil in the casing 10.

Means are preferably provided to protect the main body of oil in the casing 10 from undue agitation by the rotor 15 which would tend to cause foaming of the oil and consequently decrease the efficiency of the oil propelling mechanism. For this purpose there is provided a baffle element 104, which in the present instance, is formed with a sleeve part 105 and a collar part 106. The lower part of the sleeve 105 is formed so as to closely embrace the annular casing 18 fixed to the stationary bearing element 14, as previously described. Sleeve 105 may be secured to the casing 18 in any desired manner to prevent slippage of the sleeve thereon. As indicated in Fig. 1, the casing 18 projects outwardly somewhat beyond the surface of the rotor 15, leaving a space between the rotor and sleeve 105. It is to be noted that oil passing out through the duct 102 will impinge against the inner face of the sleeve 105 and a small body of oil will be caused to collect in this space. Due to this arrangement there will be little tendency to agitation of the oil by reason of the movement of the

stream of oil through the duct 102. In order to permit oil to flow from the space between the baffle element and the rotor 15, there is preferably provided an opening 107 in the sleeve 105 of the baffle element. Due to the provision of this opening there will be a more or less constant stream of oil flowing from the opening 107 during the operation of the unit. The collar element 106 of the baffle is spaced down below the lower surface of the motor armature 25 and extends substantially to the inner face of the field winding 27.

It is to be noted that the rotor 15, as it rotates in a clockwise direction, will tend to carry the oil downward through the spiral groove 100. This movement is also caused in part by pressure of oil from the upper end of conduit 66.

Small quantities of oil will tend to pass out into the compression chambers of the cylinders 0 along the cylinder walls and also through the piston ducts. This oil will pass through the cylinder discharge valves and keep such valves lubricated. The oil passing through the cylinder discharge valve will be thrown outwardly and 5 will impinge upon the walls of the casing 10 where it will flow back into the oil supply at the bottom of the casing.

While, in the foregoing description, the device has been described as preferably one in which 0 the rotor operates on an upright or vertically disposed axis, it is not to be understood that the device is necessarily limited to use in such a position as certain aspects of the device are equally well adapted for operation where the 15 rotor element rotates about a horizontal axis. Thus, the terms upright and horizontal, when used herein, are to be understood as used in a relative sense and for convenience of description, except where the context necessarily requires a limitation to a particular arrangement.

From the above description it is apparent that the present invention provides a gas compressor unit having few operating parts and having combined therewith an effective lubricating arrangement whereby operation of the unit will initiate operation of the lubricating elements causing a constant pressure delivery of oil between relatively movable contacting surfaces as long as the unit remains in operation. Due to 10 the arrangement in which oil is forcefully fed to bearings and other contacting surfaces, all parts requiring lubrication will receive oil in necessary quantities and the effective life of the unit will be prolonged.

While the present description sets forth a preferred embodiment of the invention, numerous changes may be made in the construction without departing from the spirit of the invention, and it is therefore desired that the present embodiment be considered in all respects as illustrative and not restrictive, reference being had to the appended claims rather than to the foregoing description to indicate the scope of the invention.

I claim:

1. A liquid delivery pump for oil and similar liquids comprising a rotor, a stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, means for delivering liquid to said channel, a propelling element supported on the rotor

and extending into the annular channel to cause a flow of liquid in one direction therein upon rotation of the rotor, the stationary bearing element having an axially extending duct formed therein, connected to said channel and being connected to the liquid delivery conduit by a radially extending duct formed in the stationary bearing element, whereby liquid moving around the channel will pass into said axially extending duct under the action of centrifugal force and thence through the radially extending duct and into the liquid delivery conduit.

2. A liquid delivery pump for oil and similar liquids comprising a rotor, a vertically disposed stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, said channel having its open side directed upwardly, means for delivering liquid to said channel, a propelling element supported on the rotor and extending downwardly into the annular channel to cause a flow of liquid in one direction therein upon rotation of the rotor, the stationary bearing element having an axially extending duct formed therein, connected to said channel and being connected to the liquid delivery conduit by a radially extending duct formed in the stationary bearing element, whereby liquid moving around the channel will pass into said axially extending duct under the action of centrifugal force and thence through the radially extending duct and into the liquid delivery conduit.

3. A liquid delivery pump for oil and similar liquids comprising a rotor, a vertically disposed stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, said channel having its open side directed upwardly, means for delivering liquid to said channel, a downwardly extending annular portion on the rotor projecting into and completely closing the upwardly directed opening of the channel, a propelling element extending downwardly from said annular portion into the channel to cause a flow of liquid in one direction therein upon rotation of the rotor, the stationary bearing element having an axially extending duct formed therein, connected to said channel and being connected to the liquid delivery conduit by a radially extending duct formed in the stationary bearing element, whereby liquid moving around the channel will pass into said axially extending duct under the action of centrifugal force and thence through the radially extending duct and into the liquid delivery conduit.

4. A liquid delivery pump for oil and similar liquids comprising a rotor, a vertically disposed stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, said channel having its open side directed upwardly, means for delivering liquid to said channel, a downwardly extending annular portion on the rotor extending into and

- completely closing the upwardly directed opening of the channel, a propelling element extending vertically downward from said annular portion into the channel and filling a major portion of the radial width of the channel to cause a flow of liquid in one direction therein upon rotation of the rotor, the stationary bearing element having an axially extending duct formed therein, connected to said channel and being connected to the liquid delivery conduit by a radially extending duct formed in the stationary bearing element, whereby liquid moving around the channel will pass into said axially extending duct under the action of centrifugal force and thence through the radially extending duct and into the liquid delivery conduit.
5. A liquid delivery pump for oil and similar liquids comprising a rotor, a stationary bearing element upon which the rotor is adapted to rotate, the stationary bearing element being formed with a liquid delivery conduit for delivery of the liquid therethrough, a casing surrounding the stationary bearing element, said casing having an annular liquid retaining channel formed therein, means for delivering liquid to said channel, means operable upon rotation of the rotor for causing a flow of liquid in one direction in said channel, said casing having an axially extending duct formed therein and connected to the liquid delivery conduit by a substantially radially extending duct formed in the stationary bearing element, a baffle element in said annular channel, extending axially therein adjacent the outer periphery thereof and located in close proximity with the axially extending duct and beyond same in the direction of flow of liquid around the annular channel, whereby liquid moving with momentum around the channel will impinge upon the baffle element and will be deflected to flow axially with appreciable force into the axially extending duct and thence through the radially extending duct into the liquid delivery conduit.
6. A liquid delivery pump for oil and similar liquids comprising a rotor, a vertically disposed stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, means for delivering liquid to said channel, a propelling element supported on the rotor and extending into the channel to cause a flow of liquid in one direction therein upon rotation of the rotor, said casing having a downwardly extending duct formed therein and connected to the liquid delivery conduit by a laterally extending duct formed in the stationary bearing element, a baffle element in said annular channel extending vertically therein adjacent the outer periphery thereof and located in close proximity with the downwardly extending duct and beyond same in the direction of rotation of the propelling elements on the rotor, whereby liquid moving with momentum around the channel will impinge upon the baffle element and will be deflected to flow downward with appreciable force into the downwardly extending duct and thence through the laterally extending duct into the liquid delivery conduit.
7. A liquid delivery pump for oil and similar liquids comprising a rotor, a vertically disposed stationary bearing element upon which the rotor is adapted to rotate, the stationary bearing

element being formed with a liquid delivery conduit for delivery of the liquid therethrough, a casing surrounding the stationary bearing element, said casing having an annular liquid retaining channel formed therein, a liquid reservoir located adjacent the casing, said casing being formed with an opening for admission of the liquid from the reservoir to the annular channel, a propelling element supported on the rotor and extending into the annular channel to cause a flow of liquid in one direction therein upon rotation of the rotor, said casing having a downwardly extending duct formed therein and connected to the liquid delivery conduit by a laterally extending duct formed in the stationary bearing element, a baffle element in said annular channel extending vertically therein adjacent the outer periphery thereof and located between the downwardly extending duct and the opening leading into the channel from the reservoir, the baffle element being disposed beyond the downwardly extending duct in the direction of flow of liquid around the channel, whereby liquid moving with momentum around the channel will impinge upon the baffle element and will be deflected to flow downwardly with appreciable force into the downwardly extending duct and thence through the laterally extending duct into the liquid delivery conduit.

8. A liquid delivery pump for oil and similar liquids comprising a rotor, a stationary bearing element upon which the rotor is adapted to rotate, the stationary bearing element being formed with a liquid delivery conduit for delivery of the liquid therethrough, a casing surrounding the stationary bearing element, said casing having an annular liquid retaining channel formed therein, a liquid reservoir located adjacent the casing, said casing being formed with an opening for admission of the liquid from the reservoir to the annular channel, a propelling element supported on the rotor and extending into the annular channel to cause a flow of liquid in one direction therein upon rotation of the rotor, said casing having an axially extending duct formed therein connected to the channel at one end and connected at its other end to a radially extending duct formed in the stationary bearing element, said duct being in turn connected to the liquid delivery conduit, a baffle element in said annular channel extending axially therein adjacent the outer periphery thereof and located between the axially extending duct and the opening leading into the channel from the reservoir, the baffle element being disposed beyond the axially extending duct in the direction of flow of liquid around the channel, said opening leading into the channel from the reservoir being located relatively closely to the baffle, whereby liquid entering through the casing opening into the channel will pass a major portion of the distance around the channel, and after impinging against the baffle element, will be deflected to flow with appreciable force into the axially extending duct and thence through the radially extending duct into the liquid delivery conduit.

9. A liquid delivery pump for oil and similar liquids comprising a rotor, a stationary bearing element upon which the rotor is adapted to rotate, the stationary bearing element being formed with a liquid delivery conduit for delivery of liquid therethrough, a casing surrounding the stationary bearing element, said casing having an annular liquid retaining chan-

nel formed therein, a portion of said casing extending inwardly of the channel and having a circumferentially extending face concentric with the channel, a propelling element on the rotor extending into the channel to cause a flow of liquid in one direction therein upon rotation of the rotor, said propelling element being elongated in a circumferential direction and having a radial width sufficient to extend substantially across the channel at the restricted portion formed by the inwardly extended portion of the casing, a liquid reservoir located adjacent the casing, said casing being formed with a delivery opening leading from the reservoir into the channel at a point located between the ends of the inwardly extended portion, said casing having an axially extending duct formed therein, connected to the channel at one end, there being a radially extending duct formed in the stationary bearing element and connecting the radially extending duct to the liquid delivery conduit, one end of the inwardly extending portion of the casing providing a baffle element having a face extending axially and located between the axially extending duct and the opening leading into the channel from the reservoir, whereby, when the rotor is set in rotation so that the propelling elements pass successively the axially extending duct, the baffle and the liquid admission opening from the reservoir, liquid entering the channel at said opening will flow around the channel and a portion of the liquid will impinge upon the baffle and will be forced into the axially extending duct and thence through the radially extending duct to the liquid delivery conduit.

10. A liquid delivery pump for oil and similar liquids comprising a rotor, a stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, a portion of said casing extending inwardly of the channel and having a circumferentially extending face concentric with the channel, a propelling element on the rotor extending into the channel to cause a flow of liquid in one direction therein upon rotation of the rotor, a liquid reservoir located adjacent the casing, said casing being formed with a delivery opening leading from the reservoir into the channel at a point located between the ends of the inwardly extended portion, the casing having an axially extending duct formed therein, connected to the channel at one end, there being a radially extending duct formed in the stationary bearing element and connecting the radially extending duct to the liquid delivery conduit, one end of the inwardly extending portion of the casing providing a baffle element having a face extending axially and located between the axially extending duct and the opening leading into the channel from the reservoir, said propelling element having a radial width sufficient to extend substantially across the channel at the restricted portion thereof formed by the inwardly extending portion on the casing, said propelling element also having a length in a circumferential direction greater than the distance from the baffle to the admission opening in the inwardly extending portion of the casing, whereby the admission opening will be closed periodically during the passage of the propelling element around the channel, said casing being formed with an additional admission opening

from the oil reservoir to the channel located beyond the restricted portion of the channel whereby liquid may continue to enter the channel when the first mentioned admission opening is closed by the propelling element.

11. A liquid delivery pump for oil and similar liquids comprising a rotor, a vertically disposed stationary bearing element upon which the rotor is adapted to rotate, the stationary bearing element being formed with a liquid delivery conduit for delivery of the liquid therethrough, a casing located in juxtaposition to the stationary bearing element, said casing having a liquid retaining channel formed therein, means for delivering liquid to said channel, means operable upon rotation of the rotor for causing a flow of liquid in one direction in said channel, said casing having a downwardly extending duct formed therein extending from said channel and connected to the liquid delivery conduit by a laterally extending duct formed in the stationary bearing element, a baffle element in said channel extending vertically therein and located in close proximity with the downwardly extending duct and beyond same in the direction of flow of liquid in the channel, whereby liquid moving with momentum in the channel will impinge upon the baffle element and will be deflected to flow with appreciable force into the downwardly extending duct and thence through the laterally extending duct into the liquid delivery conduit.

12. A liquid delivery pump system for oil and similar liquids comprising, a sealed casing, an upright, stationary bearing element located in the casing, a body of liquid contained in the lower part of the casing, a rotor element comprising a casing surrounding and rotatable upon the stationary bearing element, liquid propelling mechanism operative connected to the rotor casing and the stationary bearing element and located below the level of the liquid in said sealed casing, means for delivering liquid from the liquid supply in said sealed casing to the liquid propelling mechanism, said stationary bearing element being provided with passageways for the delivery of liquid to the upper end thereof and for the return of liquid to a point adjacent the lower end of the rotor casing, said rotor casing being formed with a duct to provide for the return of liquid to the body of liquid in the sealed casing, and a baffle element in the form of a sleeve surrounding the rotor and extending upwardly from a point below the level of liquid in the sealed casing to a point adjacent said duct, whereby the baffle element will receive the flow of liquid from said duct and will thereby substantially protect the body of liquid in the sealed casing from impingement of the flow from said duct and from direct contact with the rotating surface of the rotor, thus tending to prevent agitation of the major portion of the body of liquid in the sealed casing.

13. A liquid delivery pump system for oil and similar liquids comprising a rotor, a stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, a liquid reservoir surrounding said casing, said casing being formed with an opening for admission of liquid from the reservoir to the annular channel, cooperating parts on the rotor and bearing element for delivering

liquid under the pressure to the liquid delivery conduit, the stationary bearing element being formed with a liquid return conduit, said conduit terminating in a groove formed in the stationary bearing element, the rotor including an annular casing rotatable therewith and surrounding the stationary bearing element in a position to close said groove, said casing being formed with a duct located so as to be in constant communication with said groove to provide for the egress of liquid entering the groove from the liquid return conduit, and a baffle element arranged in spaced relation in front of the duct formed in said casing, adapted to receive the impact of at least a major portion of the liquid stream flowing from the return conduit, whereby the liquid will be returned to the supply in the reservoir without a substantial degree of agitation.

14. A liquid delivery pump system for oil and similar liquids comprising a rotor, a stationary bearing element upon which the rotor is adapted to rotate, the stationary bearing element being formed with a liquid delivery conduit for delivery of liquid therethrough, a casing surrounding the stationary bearing element, said casing having an annular liquid retaining channel formed therein, a liquid reservoir surrounding said cas-

ing, said casing being formed with an opening for admission of liquid from the reservoir to the annular channel, cooperating parts on the rotor and bearing element for delivering liquid under pressure to the liquid delivery conduit, the stationary bearing element being formed with a liquid return conduit, said conduit terminating in a groove formed in the stationary bearing element, the rotor including an annular casing rotatable therewith and surrounding the stationary bearing element in a position to close said groove, said casing being formed with a duct located so as to be in constant communication with said groove to provide for the egress of liquid entering the groove from the liquid return conduit, and a baffle element comprising an annular flange secured on the stationary bearing element in a position spaced from the duct in the rotor casing whereby said flange will receive the impact of at least a major portion of the liquid flowing from the return conduit, said flange being formed with a discharge opening above the normal level of liquid in the reservoir, whereby liquid may freely flow therefrom back to the liquid in the reservoir.
